UNITED STATES PATENT OFFICE.

JAMES H. REYNOLDS, OF MITTINEAGUE, MASSACHUSETTS, ASSIGNOR TO
GEORGE J. O'DOHERTY AND WALTER VANDENBURGH, OF BOSTON,
MASSACHUSETTS.

PAPER-MAKING MACHINE.

SPECIFICATION forming part of Letters Patent No. 696,595, dated April 1, 1902.

Application filed January 17, 1901. Serial No. 43,633. (No model.)

To all whom it may concern:

Be it known that I, JAMES H. REYNOLDS, a citizen of the United States of America, residing in Mittineague, in the county of Hampden and State of Massachusetts, (whose post-office address is Mittineague, Massachusetts,) have invented new and useful Improvements in Paper-Making Machines, of which the following is a specification, reference being had to the accompanying drawing and letters of reference marked thereon.

My invention relates especially to a construction of machine wherein pressure upon the pulp or paper while on the Fourdrinier wire is avoided.

In the machines now in use the pressure upon the partly-formed paper while it is on the Fourdrinier results in placing a watermark impression or mark of the Fourdrinier wire upon the paper, thus rendering it unfit for many uses and especially renders it unfit for use for photographic purposes.

The object of my invention is therefore to provide a construction of machine wherein all watermark impressions or marks of the Fourdrinier wire on the paper are avoided, and generally to provide a construction wherein the paper produced upon said machine will have a smooth clear uniform surface, free from the objectionable feature referred to.

I accomplish the object of my invention by the construction herein shown.

In the accompanying drawing, in which like letters of reference indicate like parts, I show a portion of an ordinary Fourdrinier machine with my improvement applied thereto; it being a side elevation and showing only a portion of an ordinary Fourdrinier machine back of a point adjacent to the location of the suction-box.

Generally *a* indicates the frame of the machine; *b*, the ordinary lower roll; *c*, the Fourdrinier wire; *d*, a roll over which the Fourdrinier wire passes on its return, and *e* and *f* press-rolls.

In the construction of my machine I eliminate all pressure upon the pulp or semiplastic material forming the sheet until the same

reaches the first press-rolls *e* and *f*, and to 50 maintain the Fourdrinier wire under the requisite tension and cause it to travel with the desired uniformity I prefer to arrange a roll *d*, which by preference is adjustably mounted and between which and the couch-roll *b* the Fourdrinier wire passes, the roll *d* being located with reference to the roll *b*, so as to bear with sufficient pressure to insure the passage of the Fourdrinier wire and to give it the desired rigidity. The same result 60 may of course be accomplished by the employment of idlers or stretcher-rolls suitably adjusted, and the location of the roll *d* may be changed, provided it is not so located as to bear against the pulp or sheet of paper. As 65 shown in the drawing, the paper passes from the Fourdrinier wire upon the felt belt *j* and is carried under the roll *e*, the latter being covered with felt or other suitable soft material, and from this point it may be conveyed away and treated in the ordinary manner, provided, of course, pressure is not thereafter applied in such a way as to bring about the objectionable results referred to. I prefer that the roll *d* be mounted at each end in 75 a box, which is supported by an inclined part *h*, so that if any unusual obstruction is carried along by the Fourdrinier wire damage to the wire will be avoided by a slight movement of the boxes supporting the roll *d* up 80 the inclines, and it will be seen that after the passage of the obstruction the roll *d* will return to its normal position by gravity. It will of course be seen, however, that various devices and forms of construction may be 85 employed whereby the roll *d* may be adjustably mounted to bear toward the roll *b* and automatically retreat therefrom in the event of necessity, and thus avoid the breaking of or injury to the Fourdrinier wire, thus accomplishing the same result attained by the particular form of construction herein illustrated, and it will also be seen that various changes may be made without departing from the spirit of my invention, and I do not limit myself to the exact form of construction herein shown and described.

Heretofore the couching of the paper has

been accomplished by subjecting the paper to the pressure of the coucher before it left the Fourdrinier, resulting in marking the paper with the wire-marks of the Fourdrinier.

- 5 This is objectionable, and to avoid this feature I provide means of pressing the paper after leaving the Fourdrinier, and the mechanism by which I prefer to accomplish this result comprises a press-roll *f*, having an end-
10 less felt apron *j* arranged to pass over it and carry the paper, while above the roll *f* I arrange a press-roll *e*, having its periphery covered with felt, so that the paper passes between two felt surfaces and all objectionable
15 marking of the paper is avoided. It will of course be seen that two felt-covered rolls may be employed and an independent carrier be arranged to convey the paper from the Fourdrinier to the press-rolls. I prefer, however,
20 to employ the endless felt apron *j* and the press-rolls arranged as shown in the drawing.

To prevent danger of the paper being wound upon the top press-roll *e*, I provide an uncovered roll *k*, mounted in arms *l* and resting
25 upon the surface of the roll *e*, so that if the paper accidentally adheres to the surface of the roll *e* and is carried upwardly it will be caught by the roll *k*, and as this roll is not covered the paper will stick to it more closely
30 than to the felt surface of the roll *e*, and thus be carried upwardly and removed from the surface of the roll *k* by the doctor *m*, and thus all danger of destroying the felt on the roll *e* and the endless felt belt by the accidental bunching or accumulations of pulp or paper
35 between them will be avoided.

To enable me to vary the pressure between the press-rolls *e* and *f*, I support the frame in which the top roll is mounted on pivots, so
40 that the top roll may be moved toward and from the lower roll, and weights or levers may be employed to provide superior pressure, if desired.

Having therefore described my invention,
45 what I claim, and desire to secure by Letters Patent, is—

1. In a paper-making machine, the combination of a suitable frame, a single couch-roll, a Fourdrinier wire passing over said roll, and means located immediately adjacent to said roll and beneath the lower reach of the wire, to maintain said wire under requisite tension and cause it to travel with the desired uniformity without the application of
50 pressure upon it at a point where pulp or paper is carried.

2. The combination, in a paper-making machine, of a suitable frame, a Fourdrinier wire, and means to maintain said wire taut and
55 cause it to travel without its being engaged by a roll arranged so as to subject the pulp or paper to pressure, said means consisting of a single couch-roll and a tension-roll im-

mediately adjacent thereto and beneath the lower reach of the wire.

65

3. The combination, in a paper-making machine, of a suitable frame, a single couch-roll, a tension or driving roll immediately adjacent to said couch-roll, and a Fourdrinier wire passing between said rolls on its return travel
70 after going over the couch-roll, and means to adjust said tension or driving roll against said wire and toward said couch-roll.

4. The combination, in a paper-making machine, of a suitable frame, a Fourdrinier wire, 75 a couch-roll *b*, and a roll adjustably mounted on inclined members to bear against the roll *b* and support the Fourdrinier wire therebetween after the paper has been discharged from the Fourdrinier wire, substantially as 80 shown.

5. The combination, in a paper-making machine, of a suitable frame, a Fourdrinier wire, a couch-roll, and an automatically-adjustable roll *d* arranged on inclined members to support the Fourdrinier wire and maintain it taut, said wire being pressed between said rolls after the paper has been discharged from the wire, substantially as shown.

6. The combination, in a paper-making machine, of a suitable frame, a Fourdrinier wire, a couch-roll *b*, and a roll *d* in boxes on inclined supports *h*, whereby said roll *d* constantly gravitates against said roll *b* with the wire between, below the couching-point, substantially as shown.

7. The combination, in a paper-making machine, of a suitable frame, a single couch-roll, a tension-roll immediately adjacent to said couch-roll, a Fourdrinier wire passing over 100 the couch-roll and between the couch and tension rolls, whereby said wire is maintained taut and tensioned against the couch-roll below the couching-point, a felt belt, a supporting-roll *g* for said belt, and press-rolls *e* and *f* back of the couching-point, substantially as shown.

8. The combination, in a paper-making machine, of a Fourdrinier wire, an endless felt belt arranged to receive the pulp or paper 110 after it leaves the wire, a press-roll *f* under said belt, a felt-covered press-roll *e* above said roll *f*, a roll *k* bearing against said roll *e*, and a doctor for said roll *k*, substantially as shown.

9. The combination, in a paper-making machine, of a Fourdrinier wire, press-rolls one of which is covered with felt, a roll *k* revolving against the surface of the felt-covered roll, and a doctor bearing against the surface 120 of said roll *k*, substantially as shown.
